UNITED STATES PATENT OFFICE.

JULES P. GITS, OF CHICAGO, ILLINOIS.

DESIGN FOR A RAZOR-KNIFE.

57,636.

Specification for Design.

Patented Apr. 26, 1921.

Application filed December 22, 1920. Serial No. 432,631. Term of patent 14 years.

To all whom it may concern:

Be it known that I, JULES P. GITS, a citizen of the United States, residing at Chicago, in the county of Cook and State of Illinois, have invented a new, original, and ornamental Design for a Razor-Knife, of which the following is a specification, reference being had to the accompanying drawing, forming part thereof.

The figure is a perspective view of a razor knife showing my new design.

I claim:

The ornamental design for a razor knife as shown.

JULES P. GITS.
